(57) **CLAIM**

The ornamental design for a magnifier, as shown and described.

DESCRIPTION

FIG. 1 is a perspective view of the magnifier showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the magnifier where the magnifier is in a first configuration of use;

FIG. 10 is a left side elevational view of the magnifier where the magnifier is in a second configuration of use; and,

FIG. 11 is a perspective view of the magnifier where the magnifier is in a third configuration of use.

The broken lines in the drawings show portions of the article and form no part of the claimed design. The additional broken lines in FIG. 11 show environment and form no part of the claimed design.
